UNITED STATES PATENT OFFICE

123,086

DESIGN FOR A STAND FOR BEVERAGES, FOOD PRODUCTS, OR THE LIKE

Roderic M. Koch, Evansville, Ind.

Application May 10, 1940, Serial No. 92,289

Term of patent 7 years

To all whom it may concern:

Be it known that I, Roderic M. Koch, a citizen of the United States, residing at Evansville, in the county of Vanderburg and State of Indiana, have invented a new, original, and ornamental Design for a Stand for Beverages, Food Products, or the like, of which the following is a specification, reference being had to the accompanying drawing, forming a part thereof.

Figure 1 is a perspective view of a stand for beverages, food products, or the like, showing my design, and

I claim:

The ornamental design for a stand for beverages, food products, or the like, as shown.

RODERIC M. KOCH.
